RECUPERATOR TILE STRUCTURE

Filed Feb. 26, 1949

UNITED STATES PATENT OFFICE

2,574,738

RECUPERATOR TILE STRUCTURE

Frank H. Graham, Edgewood, and Edwin G. Smith, Mount Lebanon, Pa., assignors to Amsler Morton Corporation, Pittsburgh, Pa., a corporation of Delaware

Application February 26, 1949, Serial No. 78,644

4 Claims. (Cl. 263—20)

1

This invention relates generally to industrial heat exchangers known as recuperators and more particularly to recuperator tile structures consisting of cast or moulded parts made of refractory clay and similar materials which are assembled and cemented together with air setting cement to form a monolithic structure providing a plurality of vertical flues extending through spaced horizontal partitions that form independent horizontal passes around the vertical flues. Such heat exchanger tile structures are built inside an insulated six walled firebrick chamber for the purpose of affecting the exchange of heat from hot gases flowing through the vertical flues to air or other gases of lower temperature flowing through the horizontal passes of vice versa.

The most efficient and favored method of operating a recuperator of this type is to cause the hot gases to flow down through the vertical flues, and to introduce the air or gases to be heated at the bottom of the structure causing them to flow upward through the several horizontal passes progressively toward the top of the structure.

When operating recuperators in connection with certain types of steel mill heating furnaces, it has been found that the hot waste gases from the furnace sometimes carry with them certain finely divided dusts, parts of which are deposited on the flat surface of the top sealing course of the recuperator structure between the openings of the vertical flues where this dust forms a crustation that builds up and eventually overhangs and clogs the top openings of the vertical flues. These accumulations adhere tightly to the tile and cannot be removed without breaking or otherwise damaging the whole of the recuperator tile structure.

It has also been found that the upper portion of the monolithic recuperator tile structure may become broken or cracked making the recuperator inoperative due to accident, unusually high temperature or other causes.

One object of this invention is to retain and permit easy removal of fused dust and foreign matter accumulated above the sealing course of the recuperator structure without endangering or disturbing the recuperator structure. This is accomplished by laying an uncemented course of tile blocks and tube flues on the top sealing course of the recuperator tile structure without attaching it thereto. The tube tile projects above the tile blocks and are unsupported at their upper ends, thus forming a reservoir therebetween

2

for the accumulation of fused dust. When this reservoir becomes filled the entire course of blocks and tubes with the accumulation can readily be removed and replaced.

5 Another object is the provision of a separable and independent course above the monolithic recuperative tile structure that is thermally insulated from said tile structure and shields it from thermal shock.

10 Another object of this invention is to make it possible to remove and replace a selected number of upper horizontal courses of recuperator tile without disturbing or damaging those horizontal courses therebelow. This is accomplished by in-

15 troducing a separate course of uncemented tube tile blocks at any selected position to permit the removal of the selected separate course and all of the tile structure thereabove without disturbing or otherwise replacing the tile structure there-

20 below. The practice of this invention also permits the repair of a recuperator tile structure by smoothing off the upper surface of a selected horizontal course below the tile found to be fractured and rebuilding thereon by starting with an additional horizontal course without attaching it thereto.

Other objects and advantages appear herein-
after in the following description and claims.

The accompanying drawing shows, for the pur-
30 pose of exemplification without limiting the in-
vention or the claims thereto, certain practical
embodiments of the invention wherein:

Fig. 1 is a view in vertical section of the recuperator tile structure assembled in a refrac-
35 tory chamber and embodying the principles of
this invention;

Fig. 2 is an enlarged perspective view of the
35 flue block which is employed in the horizontal
course of the recuperator tile structure;

40 Fig. 3 is an enlarged perspective view of a center
filling block employed in the horizontal course
of the recuperator tile structure;

Fig. 4 is an enlarged perspective view of an
edge filling block employed in the horizontal
45 course of the recuperator tile structure;

Fig. 5 is an enlarged perspective view of a cor-
ner filling block employed in the horizontal
course of the recuperator tile structure; and

Fig. 6 is an enlarged view in vertical section
50 of an extra horizontal course with upstanding
tubular flues mounted on a horizontal course of
the recuperator tile structure and the parts
broken away.

Referring to the drawings, each of the tile
55 members making up the recuperator tile struc-

ture is made of a refractory material capable of withstanding the waste gas heat and a high degree of thermal shock. This recuperator tile structure is assembled within the recuperator refractory chamber 1 closed by the refractory heat insulating walls 2 and 3 in the arch roof 4 which contains the passage 5 through which the waste gases are drawn from the furnace chamber.

The bottom of the recuperator chamber 1 is provided with a bridge wall 6 designed to support the recuperator tile structure within the chamber 1 and which is provided with a plurality of openings 7 that are aligned with the vertical flues of the recuperator structure for the purpose of conducting the waste gases from the recuperator through the passage 8 to additional heat exchangers or to the stack as the case may be.

The horizontal courses of the recuperator tile structure are made up of a plurality of four different characters of tile members similar to those shown in United States Letters Patent No. 2,092,402. The flue blocks 10 as shown in Fig. 2, the center blocks 11 as shown in Fig. 3, the edge blocks 12 as shown in Fig. 4 and the corner blocks 13 as shown in Fig. 5 are all preformed tile blocks capable of withstanding considerable heat.

The flue blocks 10 are octagonal in shape and are provided with an upper recess 14 and a lower recess 15 between which is an inwardly extending flange member 16 that defines the opening therethrough. The outer surface of the block is recessed on each of the eight sides, as indicated at 17 to receive a complementary flange of the other blocks adjacent thereto or cement which interlocks it with adjacent flue blocks.

Each of the other three blocks, that is, the center block 11, the edge blocks 12, and the corner block 13, is provided with projecting flanges 18 that follow the contour of their respective block members and are arranged to fit in the grooves 17 of the flue blocks 10.

Upon constructing the recuperator tile in the refractory chamber 1, which is ordinarily square or rectangular in cross section, the corner blocks 13 are placed in their respective corners and the flue blocks 10, together with the center blocks 11 and the edge blocks 12, are interlocked and cemented together to complete in a uniform pattern the horizontal course 26 on the floor 6 at the bottom of the recuperator chamber, with the openings of each flue block being aligned with the openings 7 in the floor 6. Thus, each piece is interengaged with its adjacent piece to complete the horizontal course and the blocks are cemented together but not to the refractory chamber 1 as the refractory tile of the recuperator must be able to expand and contract within the refractory chamber 1. After the first horizontal course is completed the tubular flue members 21 are cemented in their respective sockets 14 in each of the flue blocks 10. It will be noted that the tubular flues 21 are of sufficient height to receive the whole of the flow of air or a mixture of air and gas from the inlet pipe or pipes 22 that enter the wall 2 at the bottom of the recuperator.

The second and other additional horizontal courses 23, 24 and 25 are then laid in turn on each of the series of vertically disposed tubular flues until the horizontal course 26 is reached, at which time an extra horizontal course 27 may be inserted wherein each tile block member is merely placed on top of the corresponding tile block member of the horizontal course 26 but

without cementing the upper course 27 to the lower course 26. The recuperator tile structure is then continued upwardly adding the horizontal courses 28, 29 and 31 to complete the recuperator tile structure within the refractory chamber 1, which is capped by the course of seal tile blocks having openings that are aligned with the flue tile structures as shown at 28. The course 29 is also provided with the annular sand seal 32 that extends into the recuperator wall.

At the top of the tile structure an additional or extra horizontal course 36 is added by placing the same on top of the horizontal seal course 28 of the series without cementing it thereto. An additional set of tubes is cemented in the respective sockets of the flue blocks in the horizontal course 36. The tubes as shown at 33 extend upwardly within the chamber 1. They are usually shorter than the tubes 21 but not necessarily so.

Selected center blocks 11 in the intermediate horizontal courses of the series are removed, as indicated at 34, for the purpose of providing passage for the air or gas to be heated in traversing back and forth through the horizontal passes of the recuperator tile structure from the bottom to the top thereof where it is discharged through the passage 35 and thence conducted to the furnace chamber.

A greater portion of the material, which may be carried through the passage 5 into the refractory chamber 1, will fall to the side of the tubes 33 and collect until it builds up to the top of these tubes and tends to choke or close off the bores of these tubes, at which time it will be necessary to enter the top of the recuperator and remove this material together with the whole course consisting of the blocks 36 and the tubes 33 without disturbing or otherwise destroying the horizontal courses 29 and 31. New parts for the extra upper course 36, together with the tubes 33, may then be installed and the recuperator reestablished in service without further delay.

It is also evident that in the selected horizontal courses of the recuperator structure above an uncemented joint such as between courses 28 and 27 can be removed and replaced without disturbing the structure below such a joint.

The flue blocks 10' that are to be used as the top or bottom course of a section or the masking course 36 need only one recess 14 as illustrated in Fig. 6.

While, for clarity of explanation, certain preferred embodiments of this invention have been shown and described it is to be understood that this invention is capable of many modifications, and changes in the construction and arrangement may be made therein and that certain parts may be employed without conjoint use of other parts and without departing from the spirit and scope of this invention.

We claim:

1. A refractory tile recuperator structure assembled in a refractory lined chamber, consisting of a series of vertically spaced horizontal tile courses each of which is made up of a series of flat interengaged quadrilaterally disposed flue blocks, with filling blocks including center blocks, edge blocks and corner filling blocks cemented together with the flue blocks in vertical alignment, vertically disposed tubular flues connecting subjacent flue blocks and cemented to provide independent horizontal passes and vertical flues, filling blocks at selected ends of each horizontal course being omitted to connect the horizontal

passes forming a zigzag path from the bottom of the recuperator to the top, and a separate and additional duplicate horizontal tile course having upwardly extending tubular flues above the flat tile of the course and cemented thereto, said separate and additional course mounted directly on and coordinated with one of the horizontal courses of the series without being cemented thereto for permitting the removal of said separate and additional course and the tile structure 10 thereabove without disturbing the tile structure therebelow.

2. The structure of claim 1 characterized in that said separate and additional horizontal course is mounted on the uppermost horizontal course of the series and the tubular flues thereon project upwardly above said separate and additional course and are supported only at their lower ends.

3. The structure of claim 1 characterized in 20 that said separate and additional horizontal

course is mounted on the uppermost horizontal course of the series and the tubular flues thereon project upwardly to above said separate and additional course but to a less extent than the flue separating the courses of the series.

4. The structure of claim 1 characterized in that said separate and additional horizontal course is mounted on an intermediate horizontal course of the series.

FRANK H. GRAHAM.
EDWIN G. SMITH.
